COMBINATION RECORD HOLDER AND BASE FOR RECORD PLAYERS

Lloyd F. Kurschner, Minneapolis, Minn.

Application February 27, 1952, Serial No. 18,680

Term of patent 14 years

(Cl. D33—19)

To all whom it may concern:

Be it known that I, Lloyd F. Kurschner, a citizen of the United States of America, residing at Minneapolis, in the county of Hennepin and the State of Minnesota, have invented a new, original, and ornamental Design for a Combination Record Holder and Base for Record Players, of which the following is a specification, reference being had to the accompanying drawing, forming a part thereof.

The figure is a perspective view of a combination record holder and base for record players showing my new design. The sides of the perspective view not shown in the drawing are identical with those shown.

I claim:

The ornamental design for a combination record holder and base for record players, substantially as shown and described.

LLOYD F. KURSCHNER.
